US00D852033S

(12) **United States Design Patent** (10) **Patent No.:** **US D852,033 S**
(45) **Date of Patent:** **** Jun. 25, 2019**

(54) **PACKAGE WITH ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/538,594**

(22) Filed: **Sep. 4, 2015**

Related U.S. Application Data

(63) Continuation of application No. 29/489,376, filed on Apr. 29, 2014, now Pat. No. Des. 738,204, which is (Continued)

CLAIM

The ornamental design for a package with electronic device, as shown and described.

DESCRIPTION

FIG. 1 is a bottom front perspective view of a package with electronic device showing the claimed design;

FIG. 2 is a bottom rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

(Continued)

FIG. 8 is a bottom view thereof.

The background in the figures forms no part of the claimed design.

1 Claim, 6 Drawing Sheets

Related U.S. Application Data

a continuation of application No. 29/466,605, filed on Sep. 10, 2013, now Pat. No. Des. 705,049.
